UNITED STATES PATENT OFFICE.

CHARLES L. DEPOLLIER, OF BROOKLYN, NEW YORK.

DESIGN FOR A WATCHCASE.

SPECIFICATION forming part of Design No. 26,968, dated April 27, 1897.

Application filed April 3, 1897. Serial No. 630,651. Term of patent 7 years.

To all whom it may concern:

Be it known that I, CHARLES L. DEPOLLIER, a citizen of the United States, residing at Brooklyn, in the county of Kings and State of New York, have invented and produced a new and original Design for Watchcases, of which the following is a specification, reference being had to the accompanying drawings, in which—

Figure 1 is a side view of a watchcase having my design applied thereto. Fig. 2 is a sectional view taken on the line 2 2 of Fig. 1.

The leading feature of my design consists in a ring or circle applied to the back or lid and eccentric with the scalloped periphery or outer circle of said lid.

A is the back or lid of a watchcase, and B the pendant, located at any desired point.

On the back or lid A is the ring or circle C, eccentric with the outer scalloped edge or periphery of said lid, but not meeting with or merging into the latter at any point, a space of varying width being left entirely around said circle or ring C and between the latter and outer scalloped edge of the back or lid, as shown in Fig. 1.

Having fully described my invention, what I desire to secure by Design Letters Patent is—

The design for a watchcase as herein shown and described.

CHARLES L. DEPOLLIER.
